UNITED STATES PATENT OFFICE.

PATRICK TRACY JACKSON, JR., OF CAMBRIDGE, MASSACHUSETTS, ASSIGNOR TO PAPER PRODUCTS MACHINE COMPANY, OF BOSTON, MASSACHUSETTS, A CORPORATION OF MASSACHUSETTS.

PAPER BAG OR CONTAINER.

1,333,717.

Specification of Letters Patent. Patented Mar. 16, 1920.

Application filed December 19, 1914. Serial No. 878,188.

To all whom it may concern:

Be it known that I, PATRICK TRACY JACKSON, Jr., a citizen of the United States, residing at Cambridge, county of Middlesex, 5 and State of Massachusetts, have invented an Improvement in Paper Bags or Containers, of which the following description, in connection with the accompanying drawings, is a specification, like letters on the 10 drawings representing like parts.

The invention to be hereinafter described relates to bags or other forms of containers, and more particularly to paper bags for containing granular or semi-granular material, or for serving as a protecting covering for material during shipment or storage.

As stated in an application filed by Charles H. Howard, December 12, 1914, Serial No. 876,831, for paper bag or container, 20 the recognized weakest part of a bag or other container is along the edges and about the corners, especially where the bag or container is formed of folded material, such as paper or the like. Indeed, a bag or container will frequently develop such weakness along the edges that these portions give way under the strain of the contained material while the body portion of the bag or container may still remain in substantially 25 perfect condition. In the application to which reference has been made, a good, practical means was described and claimed for giving such additional strength or reinforcement to the edge portions of bags or 30 containers, that the life of these edge portions would be prolonged in some cases to the life of the body portions of the bag or container itself.

In some cases, however, not alone are the 40 edge portions subjected to the strains, wear, and friction to which said prior application refers, but other portions of the bag or container are exposed to special strains and frictional wear. For instance, where certain kinds of material is shipped, stored, 45 or handled in a bag or container, the latter is made to stand upright on the bottom portion thereof, so that the strains and wear that act peculiarly to rupture the bag or container along the folded edge line and as 50 stated in said application, also act with more or less rupturing tendency over the entire bottom or side edge portions of the bag or

container. Where potatoes, coal, or other semi-granular material is shipped or stored 55 in bags, it is the custom to stand the bags on end, either with or without closing the mouth of the bag, and in such cases it will be noted that not only is the folded edge of the bag subjected to strains and wear tending 60 to rupture the bag along such line of fold, but the entire bottom portion of the bag is called upon to resist the internal strains and frictional wear incident to such use. The same is true of the side edge portions of the bag, especially where the bag is laid upon such edge. Toward the top and the median portions of the sides, the bag is subjected to much less strains and wear.

With these facts in mind, the objects and 70 aims of the present invention are to provide a bag or other container with reinforcing threads adhesively secured thereto and of maximum reinforcing effect at the weakest part of the bag or container, and of gradually diminishing reinforcing effect toward 75 those parts of the bag or container that are less liable to rupture, all as will hereinafter more fully appear. This maximum reinforcing effect may be secured by adhesively 80 securing larger or stronger reinforcing threads at and adjacent the folded edges of the bag or container, and gradually decreasing the size or strength of the threads from the bottom to the top or from the side 85 edges to the median portion of the sides. Obviously, also, the same conditions may be secured by increasing the number of reinforcing threads at the bottom or sides by placing them closer together and progressively separating them more and more from 90 the bottom to the top or from the sides toward the median central portion, as will more fully appear. In either case, however, the bag or container will have a maximum 95 reinforced zone where it is weakest and subjected to the greatest wear and strains, and from such zone the reinforcement will progressively decrease.

In the drawings:—

Figure 1 is a perspective view of a container or bag embodying the present invention;

Fig. 2 is an enlarged section on the line 2—2, Fig. 1;

Fig. 3 is an enlarged section on the line

100

105

3—3, Fig. 1, showing the overlapping parts separated for clearness; and

Fig. 4 is a section similar to that of Fig. 2, showing the reinforcing threads closer together at the bottom of the bag or container and progressively separated more and more toward the top of the bag.

The container may be of any appropriate shape for its intended use, and as shown in the drawings, is exemplified as a paper bag, substantially as indicated in Fig. 1.

The container or paper bag may be appropriately formed from a blank, which, when folded into the desired shape with the parts secured together, may present the general configuration as indicated in Fig. 1, wherein the side portions 2 may extend continuously from the mouth of the bag and around the bottom, while the side edge portions may be formed by parts of the blank being overlapped and appropriately secured together by an adhesive, or otherwise.

In the invention as illustrated, the paper bag is preferably formed of two plies of paper 3, 4, which may be secured together, preferably by a water-proof material, and when folded into the finished articles, has extended along its bottom and along its vertical sides, a folded edge. This characteristic fold in a bag formed of paper is emphasized, as will be readily understood, when the bags are in flat condition during shipment and storage; and as pointed out in the application hereinbefore mentioned, such folded edge portions are preferably reinforced by a longitudinal reinforcing thread, cord, tape, or the like, which will hereinafter be designated as a reinforcing thread.

When a bag or container, as hereinbefore generally constructed, is filled with granular material or semi-granular material, and is stood on end, not only is the folded edge portion thereof subjected to excessive strain and frictional wear, but a zone of the bag or container is flattened out to some extent to provide a base support, and this entire zone is thus subjected to substantially the same wear and frictional destructive forces that pertain to the folded edge. The present invention contemplates, therefore, such reinforcement of the bag or container by reinforcing threads adhesively secured thereto, that such zone of the bag which is subjected to rupturing strains and frictional wear, shall be reinforced to a maximum extent and that the other portions of the bag or container extending from said zone, shall be reinforced less and less as the distance from said zone increases.

In carrying the invention into practical effect, the bottom folded edge 5 of the bag or container may have extending longitudinally thereof, a heavy or large reinforcing thread 6, Figs. 1 and 2, adhesively secured

thereto; and at each side of the heavy or large reinforcing thread 6, other reinforcing threads 7, 8, 9 and 10, Fig. 2, of gradually diminishing size, are disposed, preferably parallel to the heavy reinforcing thread 6. 70

From the construction thus far described, it will be apparent that the bottom portion of the bag or container is not only reinforced along the folded edge by a heavy reinforcing thread, but that portions of the bag at each side of the heavy reinforcing thread, are reinforced by threads gradually decreasing in reinforcing effect toward the top or mouth of the bag, the construction being such that when the bag or container is filled with granular or semi-granular material and is stood upon the bottom portion thereof, such bottom portion flattens out to some extent and the zone of maximum reinforcement at the bottom of the bag serves to give a requisite strength 85 not only to the folded edge at the bottom, but also to those portions of the bottom at each side adjacent thereto, such zone of reinforcement gradually diminishing in reinforcing effect toward the upper portion of 90 the bag where such maximum reinforcement is unnecessary.

As a further means for giving strength and wear-resisting qualities to the bag thus formed, other threads 11 may extend longitudinally of the side portions 2 of the bag continuously around the bottom of the bag and overlie the graduated reinforcing threads hereinbefore described.

The side edge portions of the bag are also 100 subjected to excessive strains tending to rupture the bag along the folded edge 12, and at parts adjacent thereto, and the present invention contemplates provision of heavy reinforcing threads 13 extending longitudinally along the side edge portions, as indicated in Fig. 3, and other longitudinally-extending threads 14, 15, 16 and 17, of gradually diminishing size, extending substantially parallel to the heavy reinforcing 110 threads 13 at the side edge portion, substantially as indicated in Fig. 3. These side edge portions of the bag may be appropriately formed by overlapping the edge portions 18 and 19, Fig. 1, which may be secured together by appropriate means, such as an adhesive or otherwise, and such overlapping portions at the side edge portions of the bag may have longitudinally extending threads 14, 15, 16 and 17 thereof, crossed 120 by other threads 20, as indicated in Fig. 3, the construction being such that the side edge portions of the bag are reinforced in a manner similar to the bottom portion of the bag, as hereinbefore described, by means 125 of reinforcing threads which form a zone of maximum reinforcing effect along the side edges and portions adjacent thereto, and gradually diminish in their reinforcing effect toward the median or central portion 130

of the sides 2 of the bag, all of which will be clearly evident from Figs. 1 and 3.

When the bag is formed of two plies of paper, 3, 4, as indicated in the drawings, 5 the crossed reinforcing threads are preferably contained between the two plies of paper material, and secured thereto by an adhesive which, if desired, may be of waterproof character.

10 In Fig. 4, is shown a paper bag formed of two plies of paper similar to that hereinbefore described, inclosing between them and adhesively secured thereto, the crossed reinforcing threads; but instead of making 15 the reinforcing threads along the bottom edge portion of the bag of heavy or strong character and progressively diminishing the size of the threads parallel thereto at each side of the edge toward the top of the bag, 20 the modified form of the bag illustrated by Fig. 4 shows the reinforcing threads 21 at the bottom of the bag of substantially the same size, but to effect the maximum reinforcing effect at the bottom portion of the 25 bag, these threads about the bottom portion of the bag are placed closer together and are gradually separated more and more in their parallel relation toward the top of the bag. Obviously, the same effect can be 30 secured along the side edge portions of the bag by spacing the threads closer together along the side edge portions and gradually separating them more and more toward the median or central longitudinal portion of 35 the bag.

From the construction described, it will be apparent that the present invention supplies to the bag maximum reinforcement at that portion of the bag which is subjected 40 to the greatest strains and wear, and gradually diminishes this reinforcement toward those portions of the bag where the wear and strains are less, thus providing a bag or container which shall be responsive throughout 45 its construction to the proportional strains and wear incident to the different portions of the bag or container when in use.

What is claimed is:—

1. A bag or container which is formed of 50 two superposed plies of paper secured together by a waterproof adhesive and has embedded in the waterproof material between the two plies of paper a series of unwoven reinforcing filaments which extend 55 longitudinally of the sides of the bag and about the end thereof, the side edges of the bag being formed of overlapping flaps and providing a maximum strength to the bottom side edges of the bag, said unwoven 60 reinforcing filaments being of greater strength along the side edges of the bag than along the parts intermediate the side edges.

2. A bag or container formed of two 65 superposed plies of paper having a layer of waterproof adhesive between them and connecting them together, a series of unwoven reinforcing filaments extending circumferentially of the bag and embedded in 70 the waterproof adhesive which secures the two plies of paper together, the reinforcing filaments along the bottom of the bag being of greater strength than at the top, and the side edges of the bag being overlapped to 75 form a side seam for the bag.

3. A paper bag or container formed of two separate plies of paper sheets secured in superposed relation by a waterproof adhesive, a series of unwoven reinforcing filaments extending longitudinally and circumferentially of the bag and embedded in the waterproof adhesive which connects the two superposed plies of paper, the reinforcing filaments being of greater size along the bottom and side edges of the bag, and the side edges of the bag being overlapped to provide a four ply thickness of reinforced 85 waterproof material.

In testimony whereof, I have signed my 90 name to this specification, in the presence of two subscribing witnesses.
